DESIGN FOR A COFFEE PERCOLATOR

Harry Lehman, Brooklyn, N. Y.

Application November 22, 1934, Serial No. 54,117

Term of patent 7 years

To all whom it may concern:

Be it known that I, Harry Lehman, a citizen of the United States of America, residing at Brooklyn, county of Kings, and State of New York, have invented a new, original, and ornamental Design for a Coffee Percolator, of which the following is a specification, reference being had therein to the accompanying drawing, forming part thereof.

In the drawing, Figure 1 is a front elevation of a coffee percolator showing my new design; and Figure 2 is a side elevation thereof.

I claim:

The ornamental design for a coffee percolator, as shown.

HARRY LEHMAN,
